DESIGN FOR A BASKET

Mildred Rajah, Buffalo, N. Y.

Application December 20, 1944, Serial No. 117,005

Term of patent 7 years

(Cl. D58—4)

To all whom it may concern:

Be it known that I, Mildred Rajah, a subject of the King of England, residing at Buffalo, in the county of Erie and State of New York, have invented a new, original, and ornamental Design for a Basket, of which the following is a specification, reference being had to the accompanying drawing, forming a part thereof.

Figure 1 is a perspective view of the basket. Figure 2 is a cross section taken in the plane of line 2—2, Figure 1.

The body and handle of the basket are covered with a tissue-like paper made up of rows of looped strands disposed in juxtaposition and forming an over-all fluffy appearance.

I claim:

The ornamental design for a basket, substantially as shown and described.

MILDRED RAJAH.
